GOLF CART

Bryant S. Procter, Chicago, Ill.

Application October 21, 1943, Serial No. 507,108

7 Claims. (Cl. 280—51)

1

This invention relates to golf carts, that is, to golf club carrying vehicles for use primarily on golf courses to relieve the player or his caddy of the tiring exertion required to carry the weight of a set of golf clubs.

The main objects of the invention are to provide a golf cart which may be readily adapted to carry various types of golf clubs or caddy bags; to provide an improved bag construction, especially adapted to use as a part of a golf cart although not restricted thereto, whereby the golf clubs may easily and quickly be inserted and removed and whereby the clubs may conveniently be carried in relatively independent pockets so as to be thereby maintained out of contact with each other; to provide an improved bag structure wherein the clubs may be carried head down or shaft and grip up so as to be readily and conveniently accessible in playing position; to provide an improved bag which will effectively hold the club in the desired upright position without objectionable shifting; and in general it is the object of the invention to provide an improved golf club cart and bag of the character indicated.

Other objects and advantages of the invention will be understood by references to the following specification and accompanying drawings (3 sheets) wherein there is disclosed a selected embodiment of the improved structure.

In the drawings:

Figs. 1 and 2 are perspectives illustrating the improved structure, a cover member being illustrated as applied to the normally exposed portions of the clubs in Fig. 2;

Fig. 3 is a vertical cross section on a plane represented by the line 3—3 of Fig. 1;

Fig. 4 is a cross section on the line 4—4 of Fig. 3;

Fig. 5 is a fragmentary perspective illustration of the upper end portion of the golf club receiving bag in an inclined position;

Fig. 6 is a perspective similar to Fig. 1 but showing a modified arrangement in which the cart is adapted for carrying a different type of golf club bag; and

Fig. 7 is a section on the line 7—7 of Fig. 6.

Figs. 8, 9, and 10 are diagrammatic illustrations of one method of constructing a preferred form of golf club bag forming part of the invention.

Referring now to the drawings, the golf club cart therein illustrated comprises a shallow tray-like base 10, preferably made of metal. The tray is provided near one side edge with upstanding rods 11 having laterally outwardly offset end por-

2

tions constituting axles for suitable wheels 12. The rods 11 may be welded or otherwise rigidly secured to the ends of the tray 10, and if desired, braces such as indicated at 13 may be provided between the upper portions of the rods 11 and frame members 14 which are extended upwardly from the opposite ends of the tray.

The frame members or arms 14 may be in the form of metal tubes, or of any other sufficiently rigid form, and are welded or otherwise secured at their lower ends to the sides of the tray 10 approximately midway of the width of the tray. A U-shaped handle member 15 comprising side legs 16—16 and a cross arm portion 17 has the free ends of its legs 16—16 detachably connected to the upper ends of the frame members 14—14. The detachable connection between the ends of the handle member 15 and the upper ends of the frame members 14 may be of any suitable form, one arrangement being illustrated in Fig. 7. As shown in Fig. 7 the lower ends of the handle member sides 16 are each provided with a rod element 18 welded or otherwise secured to the handle, and having a portion 19 projecting beyond the end of each handle side 16. The projecting portions of the rods 18 fit telescopically into the upper end portions of the frame members 14. Suitable detachable fastenings 20 may be employed for holding the handle structure in assembled relation to the frame members.

A bag 21 is seated in the tray 10 and secured in place by means such as straps 22—22 (Fig. 1) embracing the frame members 14—14 or by means of continuous tube-like members 23—23 secured to the opposite sides 24—24 of the bag. By using straps and buckles such as shown at 22 for securing the bag in place, the bag may be readily removed or applied to the cart but when the tube 23 is employed, it is necessary to remove the handle part 15 in order to permit the bag 21 to be removed.

In addition to the side walls 24—24, the bag 21 comprises an opposite pair of walls 25 and 26, and partitions 27 and 28. The various side walls and partitions are stitched together or otherwise suitably united and they may be made of material such as canvas, leather, or other, preferably soft and flexible, material. The bottom portion of the bag may include metal or other reinforcing bottom and lower marginal elements 29 and 30 respectively (Fig. 3). As shown, the bag is preferably of two ply construction and the reinforcing elements are interposed between the inner and outer plies of the structure. The partition 27 which extends from one side wall

24 to the other side wall 24 is also preferably reinforced by means of a plate 31 which is disposed between the plies of the partition. The partitions or dividers 28 which extend transversely of the main side to side partition 27 are here illustrated as being without reinforcement although they may, if desired, have suitable reinforcements incorporated therein.

The sides 24—24 of the bag are of somewhat tapered form as shown in Fig. 3. At their lower ends they are of such width that the pockets formed on opposite sides of the main partition 27 are of a front to back dimension, that is of a dimension from the outer wall 25 or 26 to the main partition 27, which approximates the toe to heel dimension of a golf club when placed in the bag with its shaft approximately aligned with the length of the bag. This relation is indicated in Fig. 3. The sides 24 taper upwardly to slightly reduce the front to back dimension of the pockets and the upper portions of the sides are sharply narrowed to provide restricted entrance openings 32 to the respective pockets.

The entrance openings are restricted to such an extent that the front to rear dimensions thereof approximate the top to bottom dimension of a golf club head.

The two series of pockets thus formed on opposite sides of the partition 31 have their outer or front walls spaced from their respective back walls (the partition 27), a distance which at the bottoms of the pockets will accommodate the club heads in the inclined position represented in the drawing (Fig. 3), and said front to rear dimension may be tapered slightly upwardly as shown. At the upper ends of the pockets, the outer or front walls thereof are so formed that they have downwardly converging, neck, and downwardly diverging shoulder portions. The said shoulder portion serves to increase the front to rear dimension of the neck portion to permit downward movement of the club when the shaft is rocked toward its upright position in parallelism with the depth or length of the pockets. The downwardly converging upper end portion provides a flared mouth, which facilitates insertion of the clubs and constitutes an important convenience. As shown, the combined vertical dimension of said converging, neck and shoulder portions comprises a minor portion of the whole depth of the pocket.

The width of each pocket, that is to say the dimension of the pocket between adjacent transverse partitions 28, and between the outermost partitions 28 and the respectively adjacent side walls 24, approximates the normal transverse dimension of the golf club head which the pocket is designed to receive. The partitions 28 are in substantially parallel relationship to each other and to the side walls 24 so that they do not vary in their breadth.

The depth or length of the bag is subject to considerable variation but I have found that a bag which is in the neighborhood of 18 inches in length, is very satisfactory.

A golf club may easily and quickly be inserted in the proper pocket of the bag, head first in the manner indicated in Fig. 3. As there shown, a golf club 33 is illustrated in its initial position for insertion into the pocket of the bag. As there shown, the head 34 of the club is passed endwise, toe first, through the restricted mouth or entrance to the pocket. When the head of the club is inserted to the extent that the lower end of the shaft 35 engages the upper end of the bag,

or shortly prior thereto, the club may be swung upwardly so as to align the length of its shaft 35 with the length of the pocket whereupon the club will freely descend in its pocket and come to rest with the club head in the bottom of the bag as shown.

The entrance openings are preferably made so as to fairly snugly fit the club head in its passage through the mouth portion of the bag so that only a very limited shifting of the shaft in the mouth portion of the bag will be possible when the club is fully inserted therein. Because of the position of the club in the bag, its weight normally tends to cause the shaft of the club to rest against the main partition 27 as illustrated. Removal of a club from the bag is, of course, accomplished by reverse movement of the club. This arrangement permits the player to initially grasp the handle or grip portion of the desired club so that he immediately has the club in approximately playing position. Similarly, when the player is through with his stroke or shot, it is a most simple and convenient matter to reinsert the club into the bag.

The bottom of the bag may, if desired, be lined with any desired soft, cushioning material which will protect the club head against scratching.

While the player is making his stroke or awaiting his turn, the cart will normally be disposed in an upright position as shown in Fig. 3 wherein it rests at one side on the wheels 12 and, near its opposite side, directly on the ground as indicated at 40. During movement along the course, the cart will normally be tilted about the axles of the wheels 12 and drawn behind the player or his caddy through the agency of the handle part 17. The upper end portion of the bag in such inclined or travelling position, is illustrated in Fig. 5.

When the bag is in the inclined position in which it is normally propelled, the club shafts will, of course, tend to rest on the then lowermost portions of their respective pocket walls. To relieve the pockets of excessive strain incident to the weight of the club shafts and to assist in supporting the clubs from the frame arms 14, there is provided a strap 41, which may be an endless fabric strap or any other suitable band structure. The band 41 has one reach extended across and secured to the upper portion of the bag wall 25, from whence it extends around the outside of each of the frame arms 14 and across the space between the said frame arms 14. The reach 42 of the band thus approximately coincides or registers with main partition 27 and cooperates therewith to support the clubs in the uppermost set of club pockets when the bag is in tilted position. The strap is freely slideable around the frame arms 14 so that the weight of the clubs in the uppermost set of pockets tends to force the reach 42 of the strap downwardly thereby pulling up on the reach 43 of the strap which is secured to the upper marginal portion of the lowermost wall of the bag. Thus, the weight of the upper clubs tends to counterbalance the weight of the lowermost group of clubs. This counterbalancing arrangement assists in preventing excessive sagging of the upper portion of the bag and relieves the fastenings, by which the bag is secured to the arms 14, of heavy strain. The described strap arrangement also tends to maintain the clubs more nearly in their normally aligned relation to the frame arms 14. The strap 41 may be made of sufficiently stout material so that its replacement should not be necessary but

replacement may, of course, be easily made should it be required.

Suitable pockets such as indicated at 44 and 45 may be provided on the opposite faces of the bag for holding various accessories and equipment such as is carried by golf players.

The handle 15, preferably, has its upper end portion angularly offset, as shown in Figs. 1 to 3, inclusive, so as to avoid interference with the upper ends of the club shafts and to facilitate propulsion of the cart at a satisfactory upright angle which will resist movement of the clubs outwardly of the bag.

For covering the exposed shaft and grip portions of the clubs when in the bag, as shown in Fig. 1, there may be provided a hood 36, preferably of a soft flexible waterproof material. The hood is closed at its upper end, and at its bottom end is provided with short slits or slots such as indicated at 37 to permit the lower marginal portion of the hood to be fastened around the upstanding frame members or arms 14 by means such as a strap and buckle, snap or slide fasteners or simple tie cords as indicated at 38. If desired, the hood 36 may be provided on its opposite faces with a slide fastener or otherwise suitably closable slit 39 extending between points closely adjacent the upper and lower ends of the hood. When the hood is provided with such slits, it may be permitted to remain in place and the slits opened to permit withdrawal and reinsertion of the clubs in rainy weather, thereby assisting materially to keep the grip portions of the clubs dry.

The cart structure disclosed in Figs. 1 to 3, inclusive, may be employed for supporting and propelling the conventional caddy bag which is approximately twice the length of the improved bag above described. When a conventional bag is to be carried, the improved bag structure is removed from the tray and the conventional bag seated therein between the upstanding arms 14 to which the bag may be strapped.

To further facilitate the employment of the cart structure for supporting the conventional caddy bag, there may be provided an auxiliary or supplementary handle structure 46 (Fig. 6) which is interchangeable with the handle structure 15. The auxiliary or replacement handle structure 46, like the handle structure 15 is equipped with suitable pins 47, portions of which are insertable in the hollow upper ends of the side frame arms 14 of the main cart structure. Detachable fastenings such as already referred to may be employed for securing the auxiliary handle structure to the arms 14-14.

The auxiliary handle structure 46 has short free end portions 48 of its side arms arranged to extend in longitudinal alignment with the arms 14-14 and the major portions of the side arms of the handle structure 46 are angularly offset as clearly shown in Fig. 6. The angularly offset portions 49 are considerably longer than the angularly offset handle portions of the first described handle structure 15 so that the cart may conveniently be propelled at an even more upright position than is the case with the handle structure shown in Figs. 1 to 3. Such more nearly upright positioning of the cart is particularly desirable when a conventional caddy bag (represented in broken lines at 50 in Fig. 6) is carried, since the clubs are less securely retained in this type of bag. Also, the center of gravity of the top-heavy conventional bag of clubs is placed more nearly in vertical alignment with the wheel axles whereby ease of handling is at-

tained. The portions 48-48 of the auxiliary handle structure may be interconnected by means of a suitably bowed metal strap member 51 which may be riveted or otherwise permanently secured to the portions 48. Such bowed strap will constitute a support for the bag 50 and a suitable strap extending from one of the handle portions 48 to the other around the bag in an opposed relation to the strap 51 may be employed to securely hold the bag against the supporting member 51.

The interchangeable handle arrangement just described is highly advantageous to the manufacturer of golf carts, to golf course operators and to golf players. The manufacturer is required to produce only one type of main cart structure and to supply either or both of the two forms of handles described. This adaptability of the main cart structure greatly facilitates production since the main body of the structure may be standardized for the required volume production. The two types of handle structure are each of such simple form that they present no problem of production or interchangeability. Similar advantages accrued to the golf course operators and to the individual owner of the golf cart, who may at times require carts of one type and not the other, the described structure being readily adaptable to either requirement.

Referring again to the golf club bag part of the described structure, it will be apparent that the bag itself may be constructed in any suitable manner. It is, of course, preferable that the bag be more or less self sustaining in respect of its shape and especially in respect of its vertical dimension. As already indicated, the bag may conveniently be of two-ply canvas or other flexible material suitably reinforced or stiffened. One suitable form of construction is more or less diagrammatically illustrated in Figs. 8, 9, and 10.

As indicated best at Fig. 8, the opposed side walls 25 and 26 and the main partition 27 are formed of strips of selected fabric folded upon themselves as indicated at 55, the folds 55 forming the upper ends of the respective walls and partitions.

The pockets 44 and 45 are stitched as indicated at 56 to the outermost ply or fold of the respective walls 26 and 25. The partition members or dividers 28, either of single or double ply construction are stitched along their outer edges to the respective walls 25 and 26. The stitching, which unites the partitions 28 to the outer walls 25 and 26, extends through edge portions of the partitions and through only the inner ply of the side walls 25 and 26 in the areas thereof which are covered by the pockets 44 and 45. Above and below the respective pockets, the stitching preferably extends through both plies of the respective outer side walls, as shown at 57 and 59. However, it will be apparent that, if preferred, the stitching which unites the outer edges of the partitions 28 to the respectively adjacent outer walls may extend through only the inner plies of said side walls throughout their vertical dimensions.

The inner edges of the transverse partition 28 are secured to the respectively adjacent plies of the two-ply main partition 27 by stitching indicated at 60 and 61.

The lower marginal reinforcements 30 are preferably enclosed in retaining pockets formed in the respective side walls and a preferred arrangement for housing such reinforcements is shown in Fig. 10. As there shown, the two-ply side wall

28 consists of an inner ply 62 and an outer ply 63. To the outer ply 63 there is secured at 64 a horizontally extending fabric strip 65. The strip 65 cooperates with the lower marginal portion of the outer ply 63 to form a pocket for receiving the reenforcement 30. The lower edge of the strip 65 may also be secured as indicated at 66 to the outer ply 63. Said lower edge may be additionally or solely secured to the outer ply 63 by means of stitching 67 which also serves to unite the edge of bottom fabrics 68 to the lower edges of the outer side walls. The stitching 67 preferably extends through both plies of the bottom and side walls. It will, of course, be understood that a pocket formation such as just described for housing the lower marginal reenforcement 30 will be formed on each of the four side walls in a similar manner. The reenforcement may be inserted into the pocket through the open lower edge of the pocket just before applying the stitching 67 if such stitching is relied upon to the exclusion of the stitching 66 for closing the bottom of the bag. However, if the stitching 66 is employed, the reenforcement 30 may be inserted endwise into the pocket after the strip 65 is attached at both its top and bottom edges to the wall ply 63.

In the procedure of assembling and forming the bag, it has been found practicable to first attach the pockets 44 and 45 to the outer plies of the walls 26 and 25, respectively, then to attach the outer edges of the partitions 28 to at least the inner plies of the respective outer walls if not to both plies of the respective walls in the portions of those walls which are not covered by the pockets 44 and 45 or the reinforcements 30. It will be understood that the attached pockets 44 and 45, would seriously hamper if not prevent the machine stitching of the outer edges of the partitions 28 to both plies of the side wall without also stitching down the pockets in line with the respective partitions 28. Attachment of the partitions 28 to both plies of the side walls 25 and 26 where practicable is desirable because of the bag stiffening effect thereby produced. The inner edges of the partitions or dividers 28 are next advantageously secured to the respectively adjacent plies of the main partition 27. It will be seen that the partition 28a may have its inner edge stitched to the adjacent ply of the partition 27, then the inner edge of the partition 28b and so on, all of the partitions 28 on one side of the main partition 27 being successively joined to the adjacent ply of the main partition 27. In a similar manner the transverse partitions 28 on the other side of the main partition 27 are progressively secured to the adjacent ply of the main partition 27.

The next step is to secure the other pair of side walls 24, 24 to the side edges of the walls 25 and 26 and to the side edges of the main partition 27. The said side walls 24 are advantageously first united by stitching or otherwise as indicated at 69 to the adjacent side edges of the main partition 27 after which the side walls 24 may have their edges united as indicated at 70 to the respectively adjacent side edges of the walls 24 and 25.

The bottom of the bag is next put in place, the bottom reenforcement 29 being incorporated in a bottom structure having a marginal portion 71 extending therearound for facilitating the attachment of the bottom to the sides by means of the stitching 67.

Various modifications in the details of con-

struction may be made without departing from the spirit of the invention as defined in the following claims which are directed to the principal features of the improved structure rather than to the readily changeable details of construction.

I claim:

1. A golf club cart comprising a wheel supported base and a handle extending upwardly from said base, a bag carried by the cart for supporting a plurality of golf clubs in two groups separated in the direction in which the cart is rolled on its wheels, said cart being normally inclined to the vertical when being so rolled, and means associated with the upper end portion of said bag and with said handle for causing the clubs in one of said groups to more or less counterbalance those in the other group when the cart is in said inclined position.
2. A golf club cart comprising a wheel supported base, a pair of arms extending upwardly from the opposite sides of said base, a golf club bag mounted on said base intermediate said upwardly extending arms, said bag comprising four side walls forming a rectangular outer wall structure, a main partition wall extending from one of said side walls to the oppositely disposed side wall, a plurality of relatively spaced partitions extending transversely of said main partition in opposite directions therefrom to the other two outer walls, said partitions serving to divide said golf club bag into a plurality of pockets each adapted to receive a golf club, the upper portion of each of said pockets being of a dimension from their respective outer walls to the main partition which approximates the top to bottom dimension of a golf club head, the lower portions of said pockets having a corresponding dimension approaching the toe to heel dimension of a head, and means associated with the upper end of said bag and with said arms of the cart for causing the clubs in the pockets on one side of said main partition to counterbalance the clubs in the pockets on the other side of said main partition when said bag is disposed at an angle to the vertical.
3. A golf club cart comprising a wheel supported base, a pair of arms extending upwardly from the opposite sides of said base, a golf club bag mounted on said base intermediate said arms said bag comprising four side walls forming a rectangular outer wall structure, a main partition wall extending from one of said side walls to the oppositely disposed side wall, a plurality of relatively spaced partitions extending transversely of said main partition in opposite direction therefrom to the other two outer walls, said partitions serving to divide said golf club bag into a plurality of pockets each adapted to receive a golf club, the upper portions of said pockets being of a dimension from their respective outer walls to said main partition which approximates the top to bottom dimension of a golf club head, the lower portions of said pockets having a corresponding dimension approaching the toe to heel dimension of a club head, and a strap associated with the upper end of said golf club bag and having one portion extending from one of said arms to the other approximately in alignment with said main partition of said bag, around said arms and around the pockets disposed to one side of said main partition, substantially as and for the purpose described.
4. A golf club bag comprising side walls, front and back walls connecting said side walls, and a plurality of relatively spaced dividers generally parallel with said side walls and extending be-

tween said front and back walls intermediate said side walls, said dividers and side walls cooperating with said front and back walls to form a plurality of golf club receiving pockets, said bag being of such depth that the depth of each of said pockets is a plurality of times its greatest transverse dimension, said dividers being spaced from each other a distance approximating the normal transverse dimension of a golf club head, said front and back walls having upper portions spaced from each other a distance approximating the normal top to bottom dimension of a golf club head and their lower portions spaced a greater distance approximating the toe to heel dimension of the club head, the major portion of the expansion of said front to back dimension being effected in a shallow zone adjacent the upper end of each pocket whereby golf clubs are insertable into said pockets by first inserting the club head endwise, toe first, through said upper end portion of the pocket, then rocking the club to align the shaft thereof with the depth of the pocket, and then moving the club longitudinally downwardly in the pocket, the depth of the pocket being such that the upper and lower portions thereof are respectively operative to engage the shaft and head portions of the club to hold the clubs substantially upright in approximately parallel relation.

5. A golf club bag comprising a pair of side walls, front and rear walls, a partition extending from one of said side walls to the other, a plurality of dividers extending from each side of said partition to said front and rear walls respectively, said walls, partition and dividers cooperating to form a plurality of pockets each of which is adapted to receive a golf club, said pockets having lower portions of such transverse dimensions as to be adapted to accommodate the heads of the golf clubs when they are in inclined positions incident to normal vertical positions of the club shafts, and shallow upper end portions of such reduced dimension transversely of said partition as to necessitate insertion of the club heads toe first into the pockets with the shafts extending upwardly at an inclination and subsequent swinging of the club shafts upwardly toward the plane of said partition to permit the clubs to drop to the bottoms of the pockets, the depth of the bag being such as to cause said shallow upper pocket portions to cooperate with said lower portions to hold the clubs with their shafts substantially upright in approximately parallel relation.

6. A golf club bag comprising four side walls forming a rectangular outer wall structure, a main partition extending from one of said side walls to the oppositely disposed side wall, a plurality of relatively spaced dividers extending transversely of said main partition in opposite directions therefrom to the other two outer walls, an accessory pocket on the outside of one of said other outer walls, and means for reinforcing the lower marginal portions of the bag sides, said main partition and said accessory pocket bearing wall embodying sheet members folded upon themselves to provide inner and outer wall plies and a pair of main partition plies, said accessory pocket being secured only to the outer ply of said accessory pocket bearing wall, the transversely extending dividers being respectively secured at their inner edges, only to the respectively adjacent plies of said main partition, the outer

edges of said dividers being secured to the respectively adjacent outer walls, the dividers between said partition and said accessory pocket bearing wall being secured in the area of said pocket to only the inner ply of said wall, and a fabric strip secured to the lower marginal portion of the outer ply of said wall on the inside thereof for cooperating with said outer ply to form a pocket for receiving said reinforcing member.

- 10 7. A golf club bag comprising side walls, front and back walls connecting said side walls, and a plurality of relatively spaced dividers generally parallel with said side walls and extending between said front and back walls intermediate said side walls, said dividers and side walls cooperating with said front and back walls to form a plurality of golf club receiving pockets, said dividers being spaced from each other a distance approximating the normal transverse dimension of a golf club head, said front and back walls having upper portions arranged in downwardly converging relationship to provide a flared entrance, neck portions spaced from each other a distance approximating the normal top to bottom dimension of a golf club head, and shoulder portions diverging downwardly to enlarge the front to back dimensions of the pockets to permit golf clubs to be moved downwardly in the pockets, said converging neck and shoulder portions together comprising a minor portion of the whole depth of the pockets whereby golf clubs are insertable into said pockets by first inserting the club head endwise, toe first, through said upper end portion of the pocket, then rocking the club to align the shaft thereof with the depth of the pocket, and then moving the club longitudinally downwardly in the pocket, the depth of the pocket being such that the upper and lower portions thereof are respectively operative to engage the shaft and head portions of the club to hold the clubs substantially upright in approximately parallel relation.
